The ornamental design for packaging container, as shown and described.

DESCRIPTION

FIG. 1 is a perspective view of the packaging container embodying the new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a right side elevational view thereof;

FIG. 7 is a left side elevational view thereof;

FIG. 8 is a perspective view of an alternate embodiment of the packaging container of the new design showing the closure means in broken lines;

FIG. 9 is a top plan view thereof;

FIG. 10 is a bottom plan view thereof;

FIG. 11 is a front elevational view thereof; the rear elevational view being the same as FIG. 5;

FIG. 12 is a right side elevational view thereof; and,

FIG. 13 is a left side elevational view thereof.

The characteristic features of the design reside in a length-to-height ratio of about 5.5:1 combined with two torpedo-shaped lid hinges.

The broken line showing of closure in FIGS. 8-13 is for illustrative purpose and forms no part of the claim.
